US0D1022587S

(12) **United States Design Patent** (10) Patent No.: **US D1,022,587 S**
(45) Date of Patent: ** Apr. 16, 2024

(54) **HANDLE FOR MICROWAVE FOOD COVER**

(71) Applicant: **Kongxie Huang**, Fuzhou (CN)

(72) Inventor: **Kongxie Huang**, Fuzhou (CN)

(**) Term: **15 Years**

(21) Appl. No.: **35/517,592**

(22) Filed: **Jun. 8, 2023**

(80) **Hague Agreement Data**

Int. Filing Date: **Jun. 8, 2023**

Int. Reg. No.: **DM/229627**

Int. Reg. Date: **Jun. 8, 2023**

Int. Reg. Pub. Date: **Jun. 23, 2023**
